[57] CLAIM

The ornamental design for a shoe midsole side, as shown and described.

DESCRIPTION

FIG. 1 is an elevational view of one side of a shoe midsole showing my new design;

FIG. 2 is an elevational view of the other side of the shoe midsole;

FIG. 3 is an elevational view of the front side of the shoe midsole;

FIG. 4 is an elevational view of the rear of the shoe midsole;

FIG. 5 is a cross sectional view taken along line 5—5 of FIG. 2; and,

FIG. 6 is a bottom plan cross-sectional view taken generally along line 6—6 of the midsole shown in FIG. 2. The broken line showing the remaining portion of the sole and shoe upper in FIGS. 1-4 forms no part of the claimed design.

FIG. 1

FIG. 4

FIG. 3

FIG. 6
